UNITED STATES PATENT OFFICE.

HORACE FALK NEUMAYER, OF MACUNGIE, PENNSYLVANIA.

INTERNAL-COMBUSTION ENGINE.

1,116,471.

Specification of Letters Patent. Patented Nov. 10, 1914.

Application filed June 12, 1913. Serial No. 773,231.

To all whom it may concern:

Be it known that I, HORACE F. NEUMAYER, a citizen of the United States, and a resident of Macungie, in the county of Lehigh and State of Pennsylvania, have invented a new and Improved Internal-Combustion Engine, of which the following is a full, clear, and exact description.

Among the principal objects which the present invention has in view are: to provide an engine of the character named having means for successively compressing, storing, exploding and delivering the explosive fuel and expansive gases thereof; to provide an efficient system for cooling by air the operative parts of the engine; to provide an efficient system of packing the joints of the moving and stationary parts of the engine; to provide a simplified and efficient timing mechanism; and to provide a simple and efficient valve and operating mechanism therefor.

One embodiment of the present invention is shown in the accompanying drawings, in which—

Figure 1 is a front end view in vertical elevation of an engine constructed and arranged in accordance with the present invention; Fig. 2 is a rear end view of the same, the driving shaft and exhaust pipe being shown in section; Fig. 3 is a longitudinal sectional elevation, the section being taken on the line 3—3 in Fig. 4; Fig. 4 is a sectional elevation on the line 4—4 in Fig. 3; Fig. 5 is a sectional elevation on the line 5—5 in Fig. 3; Fig. 6 is a detail view of the timing lever; Fig. 7 is a detail view of the timing collar; Fig. 8 is a diagrammatic view showing the valve action of both the compression and the expansion cylinders.

As seen in the drawings, the present invention employs three distinct rotary members. The drums 10 and 11 are both rigidly mounted on the main driving shaft 12. Said drums are mounted in casings 13 and 14, respectively. The casings 13 and 14 are both rigidly mounted on a base plate 15, and are spaced apart to hold therebetween a main driving gear wheel 16, which is likewise rigidly mounted on the shaft 12. The casings 13 and 14 are connected by an elongated cylindrical casing 17, wherein is rotatively mounted a third drum 18. The drum 18 has cut in the median section thereof gear teeth 55 to form a gear toothed channel 19. The teeth of the channel 19 are meshed with the

teeth of a transmission gear wheel 20, which are likewise meshed with the teeth of the driving wheel 16.

The driving wheel 16 is formed to a diameter equal to the diameter of the channel 19, whereby is secured uniformity in the rate of rotation of the drum 18, shaft 12 and drums 10 and 11 connected therewith. In this manner, there is secured timed registration of ports 21 and 22 in the drum 18 with ports 23 and 24 communicating with the chambers of the casings 13 and 14, respectively.

The drum 18 is elongated and tubular, and is provided at each end with heads 25 and 26, forming, when secured in position, an explosion chamber, the capacity of which is calculated to produce the desired effect on the expanding gases when liberated therefrom to pass through the port 24 into the cylinder 29. The drum 18 is completely incased within the casing 17, the latter being provided with heads 27 and 28, as shown best in Fig. 3 of the drawings.

The explosive fuel which is delivered to the explosion chamber 30 in the drum 18 is compressed in the cylinder 31. The cylinder 31 is annular in shape, the outer wall thereof being formed by the inner surface of the casing 13, and the inner wall by the perimeter of the drum 10. The drum 10 is circular, while the inner wall of the casing is irregular in shape, forming a bridge 32 to divide the cylinder 31 in the manner best shown in Fig. 4 of the drawings. The thickened portion forming the bridge 32 also forms a seat for the casing 17, which is held rigidly in position upon the casings 13 and 14 by anchoring straps 33, from which straps extend outward the radiator blades 34.

In the drum 10 is formed a slot 35, in which slides a vane or piston 36. The piston 36 is furnished at the outer end with a packing 37 of any suitable material and construction, to bear against the outer surface of the cylinder 31 to completely close and divide said cylinder to form therein an induction and a compression section, said sections being behind and in front of said piston, respectively.

The bridge 32 is provided with a series of perforations 38, which register with the port 23 at the left of the vertical longitudinal plane of the engine. To the right of said vertical plane, the bridge 32 is partially bored to form a recess 39 which reg-

isters with a fuel-supply pipe 40 leading thereto from a carbureter 41. The carbureter 41 may be of any conventional type, and its disposition upon, or adjacent to, the 5 engine or casing 13 thereof may be greatly varied to suit the conditions incident to the service or installation.

The piston 36 is held outward from the center of the drum 10 by a heavy coil spring 10 42, which yields when said piston is passing under the bridge 32 to flush with the perimeter of the drum 10, to be thereafter lifted as permitted by the inner surface of the bridge 32 to pass the recess 39 and pipe 40 15 connected therewith, to trap the fuel previously delivered therefrom to the cylinder 31.

It will be noted that the port 21 in the drum 18 passes out of register with the port 23 of the casing 17 as the piston 36 moves 20 under the port 23 or perforations 38 communicating therewith. This arrangement of the drum 18 secures the closure of the port 23, and prevents the delivery of fuel from the cylinder 31 during the first half 25 of the rotation of the drum 10 after passing the recess 39 and supply pipe 40. In consequence of this action, when the port 21 is brought in register with the port 23, the fuel compressed by the piston 36 rushes 30 into the chamber 30, the accelerated speed of said fuel aiding in scavenging the chamber 30, to drive the dead gases therefrom into the cylinder 29, to be exhausted therefrom by way of a pipe 43.

35 In the operation of the engine, the drum 18 rotates to move the port 22 to register with the port 24 immediately after the closure of the port 23 by the removal of the port 21 out of register therewith. As the 40 port 22 begins to open to the port 24, the charge of compressed fuel held in the chamber 30 is exploded or fired by a spark electrically produced by a spark plug 44, the terminals whereof extend through the heads 45 26 and 28, being rigidly mounted in the former and rotatively mounted in the latter. The exploding charge and expanding gases rush from the chamber 30 to impinge on a piston 45, forcing the same and the drum 11 50 in which it is mounted, to rotate in the direction shown by the arrow in Fig. 5 of the drawings. The piston 45 is provided at its outer end with an end-opening slot 46, wherein is slidably mounted a yielding packing strip 47. The strip 47 is held outward 55 against the surface of the cylinder 29 by a cushion of spiral springs 48. In this manner, the joint between the outer end of the piston 45 and the outer surface of the cylinder 29 is maintained closed.

60 The piston 45 is held outward against the curved outer surface of the cylinder 29 by spiral springs 49, said piston being slidably mounted and guided in a slot 50 formed in 65 the drum 11, as shown best in Fig. 5 of the

drawings. To guide the action of the piston 45, and to hold the springs 49, said piston is provided with two or more guide rods 51.

In Fig. 5 of the drawings, there is shown by dotted lines the relative location of the 70 pipe 43, from which the dead or expanded gases following the piston 45, are delivered after said piston has passed said exhaust pipe.

75 It will be noted by comparison of the ports 21 and 22 in their relation each to the other and each to its respective port 23 and 24, that the last period of the passage of the port 22 into register with the port 24 is coincident with the first period of the passage 80 of the port 21 into register with the port 23. This arrangement of the various ports provides a clear passage for the compressed fuel in the cylinder 31 through the chamber 30, the cylinder 29 and the exhaust pipe 85 43, thus permitting the scavenging of the chamber 30. The dead gases remaining in the cylinder 29, consequent upon one explosion, are expelled therefrom by the piston 45 on the succeeding explosion of revolution of 90 the drum 11 and said piston carried thereby.

95 The above-described scavenging action occurs within a relatively short period of time, the port 24 being closed or determined by the rotation of the drum 18, which develops fully the opening of the ports 21 and 23 to receive the full compression of the fuel delivered by the piston 36 and the chamber 30. The port 23 is thereafter fully closed before the opening or registration of the 100 ports 22 and 24 begins. In other words, the full compressed charge of explosive fuel is for a short period held in the chamber 30.

105 Coincident with the initiation of registration of the ports 22 and 24, the charge of fuel in the chamber 30 is exploded by an electric spark developed in the plug 44. Co-incident with the development of the explosion, consequent upon the ignition of the charge, is the development of the registration of the ports 22 and 24. The timing of the explosion is regulated by the movement of a lever 52. The lever 52 is rotatively mounted on the shaft 12, and is held by a perforated quadrant 53 mounted on the casting or frame of the machine. The perforations 54 in the quadrant 53 are furnished to receive a set pin, which is compressed into said perforations by a flat spring 55 mounted on the lever 52. The lever 52 is secured 110 to a ring 56 by a plate 57 of insulating material. The lever 52 and parts connected therewith being held relatively stationary by the quadrant 53, the shaft 12 rotates within the ring 56. Fixedly mounted on 115 the shaft, to rotate therewith, is a collar 58, faced partly with insulating material 59. A portion of the metal of the collar 58 extends through the insulating material 59 to form a relatively short contact surface 60. 120

65 125

The contact surface 60, in rotating with the shaft 12, passes under the end of a wiper spring 61. The spring 61 is held in position by a screw bolt 62. A nut mounted on the bolt 62 forms a binding post for a circuit wire 63. The wire 63 is electrically connected with a battery 67. A second binding post 66 is electrically connected with the battery 67, or other electric source, by means of a circuit wire 68. The plate 64 is in circuit with one of the jump-spark terminals of the plug 44, as seen best in Fig. 3 of the drawings.

From the foregoing, it will be seen that as the lever 52 is shifted around the center of the shaft 12, the moment of contact between the surface 60 on the collar 58 and the wiper spring 61 is advanced or retarded relative to the opening of the ports 22 and 24. Thus, if desired, the moment of explosion may be predetermined, to permit the explosive fuel to partly flow into the cylinder 29 prior to explosion, or it may be advanced to explode the charge while completely in the chamber 30, and at the instant of the inauguration of the opening of the ports 22 and 24. Under all conditions, it will be understood that when the explosion occurs, the major portion of the fuel charge is contained in the explosion chamber 30.

To cool the working parts of the engine, I provide fans 70 and 71. The fan 71 is fixedly mounted on the shaft 12, to rotate therewith, and is mounted in juxtaposed relation to the outer face of the casing 13. The casings 13 and 14 are both provided with perforations or openings 72, through which the air flows lengthwise of the engine, being drawn through a bonnet 73 with which the engine is provided. The drums 10 and 11 have a spider construction; that is, outer rings are mounted on spokes spaced apart to form passages 74 through which the air drawn through the openings 72 passes to reduce the heat of said drums. The fan 71 is operatively connected by a belt 75 and a pulley 76, with a tubular shaft 77. The tubular shaft 77 is rotatively mounted on a stud shaft 78, which is rigidly mounted or set in the head 27 of the casing 17, as seen best in Fig. 3 of the drawings. The rate of rotation of the fan 70 is increased as compared with the rate of rotation of the fan 71, thereby providing for a more rapid movement of the air under the upper portion of the bonnet 73 and around the casing 17 and explosion chamber 30 therein.

In the present engine, the maximum heat is produced in the chamber 30. For this reason, the casing 17 is provided with a plurality of radiating fins 79. The fins 79 are mounted in series upon straps 80, which in practice surround the casing 17, and are utilized to bolt down or seat said casing in the seats provided therefor in the casings

13 and 14. This feature of construction is shown best in Figs. 4 and 5 of the drawings. The fans 79 are multiplied as required, to produce the maximum cooling efficiency.

The piston 45 is, as above described, lifted or maintained in contact with the outer surface of the cylinder 29 by means of the spring 49. To assist this action and at the same time a better timing of the action of the piston 45, I lift the same mechanically by a lever 81. The lever 81 is pivotally mounted, by means of a pin 82, on the drum 11. A second lever 83 is pivotally mounted by means of a pin 84 on the same drum, the two levers being connected by a rod 85, as seen in Fig. 5 of the drawings, reciprocally imparting movement each to the other.

The lever 81 is pivotally connected with the piston 45, while the lever 83 rests upon a cam disk 86, a short end 87 being provided for that purpose. The cam of the disk 86 is platted in correspondence to the curve of the outer wall of the cylinder 29, the object of the construction being to move the piston 45 in conformity to the shape of said wall.

In the present engine, I employ what may be termed an oil packing for the drums 10, 11 and 18. Said packing consists in providing annular grooves 88, to which oil is fed abundantly from oil cups 89.

The cylinders 29 and 31 are each provided with a small intake pipe 90 and a pet-cock 91 for controlling the passage through the same. The purpose of the pipes 90 and pet-cocks mounted thereon is to admit air to said cylinders to relieve the suction of the same. This is done at the beginning of the operation of the engine, or while performing what is known as "cranking" or turning over the driving shaft.

In the diagram shown in Fig. 8, the cylinders 29 and 31, and the opposite ends of the drum 18, are shown in the same plane, in order that the relation of the ports 21 and 22 to each other and their mutual relation to the ports 23 and 24 may be shown. Thus, in the drawings, 29+31 indicates the dual presentation of the cylinders 29 and 31. The heavy lines indicate the cylinder 29 and the drum 10, while the light lines indicate the cylinder 31 and the drum 11. The piston 33 in the cylinder 29 is indicated in heavy lines, while the piston 45 is indicated by light lines, the two pistons being shown in their relative positions. The drum 18, wherein is formed the ports 21 and 22, is shaded in various ways to indicate graphically the metal walls of the drum 18 and the arrangement of the port openings therein. Thus, the horizontal shade lines indicate the solid wall at the end of the drum 18 adjacent the compression cylinder 31, where the port opening 21 is formed, while the vertical shade lines indicate the solid wall at the op-

posite end of the drum 18 adjacent the cylinder 29, where the port 22 is formed. The numerals 21, as used in Fig. 8, indicate the port opening for the admission of compressed fuel to the explosion chamber 30, while the numeral 22 indicates the port opening for the passage of the expanding gases from the explosion chamber to the cylinder 29. The combined numerals 21+22 indicate the lap of the port openings 21 and 22. This lap of the port openings is utilized to permit the fresh fuel entering the chamber 30 to scavenge the same by driving the spent fuel therefrom by way of the port 24, into the cylinder 29.

In Fig. 8, the various arrows have been lettered to facilitate the reference thereto; thus, the arrow A indicates the compressed fuel passing from the cylinder 31 to the explosion chamber 30, under normal conditions. The flight of arrows B indicates the course of the compressed fuel passing from the cylinder 31 to the cylinder 29 by way of the chamber 30 to scavenge or clear said chamber of dead or spent gases. The arrow C indicates the normal passage of the exploded or expanding gases entering the cylinder 29 from the chamber 30. The arrow D is used to indicate the compression side of the piston 36. The arrow E indicates the gas-expansion side of the piston 45. The arrow G indicates the fuel passing into the cylinder 31. The arrow H indicates the passage of the dead or spent gases by way of the exhaust pipe 43. The arrows K and M are used to show the rotation of the shaft 12 and the drums 10, 11 and 18.

Claims.

1. An internal combustion engine, comprising a rotary driving shaft; a plurality of circular cylinders mounted to surround said shaft in planes perpendicular thereto, said cylinders being provided each with an inlet port and an outlet port; a plurality of pistons mounted upon, to continuously rotate with said shaft in said cylinders; a rotary cylinder extending between said circular cylinders to form a communicating passage therebetween, said rotary cylinder having port openings therein to register with one of said ports in each of said cylinders, the port openings of said rotary cylinder being arranged relatively to the ports with which they register so that both openings are partly in register with their respective ports for a period of time; and means operatively connecting said shaft and said rotary cylinder to synchronize the rotation of said rotary cylinder and said pistons.
2. In combination, a compression cylinder and an expansion cylinder coaxially disposed in separated relation; an explosion chamber extending between and in open communication with both cylinders; a cylindrical valve rotatively mounted in said cylinders, concentrically therewith; a plurality of rotary drums mounted on said shaft, one of said drums being disposed in each of said cylinders; a plurality of reciprocating pistons mounted one in each of said drums to move outward therefrom to rest against the inner walls of said cylinders; a transmission mechanism operatively connecting said shaft and valve to operate said valve in timed relation to said drums;

chamber and having ports at the ends thereof, for establishing communication between said chamber and said cylinders, said ports being disposed to relatively time the communication between said chamber and said cylinders, to secure successive operation thereof; a driving shaft mounted in said cylinders, concentrically therewith; a plurality of rotary drums mounted on said shaft, one of said drums being disposed in each of said cylinders; a plurality of reciprocating pistons mounted one in each of said drums to move outward therefrom to rest against the inner walls of said cylinders; and a transmission mechanism operatively connecting said shaft and valve to operate said valve in timed relation to said drums.

3. In combination, a compression cylinder and an expansion cylinder coaxially disposed in separated relation; an explosion chamber extending between and in open communication with both cylinders; a cylindrical valve rotatively mounted in said chamber, said valve having port openings controlling the communication between said chamber and each of said cylinders, said port openings being arranged for relatively progressive operation, to provide overlapping sections therein, whereby both cylinders and chamber are in communication; a driving shaft mounted in said cylinders, concentrically therewith; a plurality of rotary drums mounted on said shaft, one of said drums being disposed in each of said cylinders; a plurality of reciprocating pistons mounted one in each of said drums to move outward therefrom to rest against the inner walls of said cylinders; and a transmission mechanism operatively connecting said shaft and valve to operate said valve in timed relation to said drums.

4. In combination, a compression cylinder and an expansion cylinder coaxially disposed in separated relation; an explosion chamber extending between and in open communication with both cylinders; a cylindrical valve rotatively mounted in said chamber and having ports at the end thereof, for establishing communication between said chamber and said cylinders, said ports being disposed to relatively time the communication between said chamber and said cylinders, to secure successive operation thereof; a driving shaft mounted in said cylinders, concentrically therewith; a plurality of rotary drums mounted on said shaft, one of said drums being disposed in each of said cylinders; a plurality of reciprocating pistons mounted one in each of said drums to move outward therefrom to rest against the inner walls of said cylinders; a transmission mechanism operatively connecting said shaft and valve to operate said valve in timed relation to said drums;

and an ignition system embodying actuating means directly connected with said driving shaft, an electric circuit, and sparking terminals for said circuit, located in 5 said valve.

5. In combination, a compression cylinder and an expansion cylinder coaxially disposed in separated relation; an explosion chamber extending between and in open communication with both cylinders; a cylindrical valve rotatively mounted in said chamber, said valve having port openings controlling the communication between said chamber and each of said cylinders, said 10 communication with both cylinders; a cylindrical valve rotatively mounted in said chamber, said valve having port openings controlling the communication between said chamber and each of said cylinders, said 15 port openings being arranged for relatively progressive operation to provide overlapping sections therein, whereby both cylinders and chamber are in communication; a driving shaft mounted in said cylinders, 20 concentrically therewith; a plurality of rotary drums mounted on said shaft, one of said drums being disposed in each of said cylinders; a plurality of reciprocating pistons mounted one in each of said drums to 25 move outward therefrom to rest against the inner walls of said cylinders; and a train of gears operatively connecting said shaft and said valve, said gears being disposed between said cylinders.

- 30 6. In combination, a compression cylin-

der and an expansion cylinder coaxially disposed in separated relation; an explosion chamber extending between and in open communication with both cylinders; a cylindrical valve rotatively mounted in said 35 chamber, said valve having port openings controlling the communication between said chamber and each of said cylinders, said port openings being arranged for relatively progressive operation, to provide overlapping 40 sections therein, whereby both cylinders and chamber are in communication; a driving shaft mounted in said cylinders, concentrically therewith; a plurality of 45 rotary drums mounted on said shaft, one of said drums being disposed in each of said cylinders; a plurality of reciprocating pistons mounted one in each of said drums to move outward therefrom to rest against the inner walls of said cylinders; and a train 50 of gears operatively connecting said shaft and valve to operate said valve in unison with said drums.

In testimony whereof I have signed my name to this specification in the presence of 55 two subscribing witnesses.

HORACE FALK NEUMEYER.
